UNITED STATES PATENT OFFICE.

MARIA DUNHAM, OF BOYER TOWNSHIP, CRAWFORD COUNTY, IOWA.

IMPROVEMENT IN NECK-YOKE AND POLE ATTACHMENTS.

Specification forming part of Letters Patent No. **158,260**, dated December 29, 1874; application filed December 3, 1874.

To all whom it may concern:

Be it known that I, MARIA DUNHAM, of Boyer township, in the county of Crawford and State of Iowa, have invented certain new and useful Improvements in Neck-Yoke Attachments for Carriage-Poles, of which the following is a specification:

This invention has for its object to furnish simple and effective means whereby yokes may be securely attached to carriage and other draft poles, and disengaged therefrom, with ease and celerity.

The invention consists in a neck-yoke-retaining attachment for carriage-poles, consisting essentially of an arc-shaped locking-lever, which is pivoted to a metallic plate secured to the pole, and attached, at the end near its pivot, to a sliding spring-retracted bar, which is drawn outward by means of a spring-encircled stem extending through a cap-plate at the end of the pole, so that the free end of the arc-shaped locking-lever will be withdrawn from its attaching-plate to permit the neck-yoke to be attached or detached, the locking-lever at other times being firmly locked to retain the neck-yoke in position. The invention further consists in giving the spring-encircled pull-stem a longitudinal movement independent of the sliding spring-retracted bar, and in providing the same with a pin at its inner end, which is projected into or through an opening formed in the free end of the locking-lever, to retain the same in a locked position.

In the accompanying drawing, Figure 1 is a longitudinal section. Fig. 2 is a side elevation.

The pole A, which may be that of a carriage, wagon, reaper, or other draft-vehicle, is provided with a longitudinal channel or elongated cavity, B, at its forward end, for the reception of the neck-yoke-attaching devices. The attachment is made entirely distinct from the pole, and is composed of a pair of face-plates, C D, located, respectively, on the upper and lower sides of the pole, and connected at their forward ends by a cap, E, fitting on the end of the pole. Between external ears a, formed on the lower plate D, there is pivoted an arc-

shaped or curved lever, F, both ends of which extend through the plate into the cavity in the pole. The end of the arc-shaped lever F in proximity to the pivot-joint is pivoted to a longitudinally-sliding bar, G, the rear end of which carries a jointed guide-stem, H, moving in an inner guide-projection of the plate D, and having a head at its rear end. Said stem H is encircled by a spiral spring, I, which is located in rear of the guide-projection, and whose object is to retract the sliding bar G when the forward pull upon the same is discontinued. The front end of said bar carries a pull-stem, K, having an encircling spiral spring, L, and extending through the cap E of the attachment, where it terminates in a head or knob, e. The pull-stem K is attached to the sliding bar G by means of a slotted ear, M, which fits into the bifurcated end of the bar, and through which passes an attaching-pin, c. By the provision of said slotted ear the pull-stem is capable of receiving a sliding movement independently of the ear G, so as to enable it to be used for locking the free end of the arc-shaped locking-lever. The stem is, for this purpose, provided with a pin or reduced rear end, N, which slides through a projection, f, on the plate D, and enters a hole formed in the free extremity of the locking-lever. The spiral spring L of the combined pull and locking pin or stem K serves to force the same into the hole in the free end of the locking-lever after the same has been projected through the face-plate into the cavity of the pole by the retracting-spring of the sliding bar G. In order to attach the neck-yoke to the pole, all that is necessary is to pull the stem K in an outward direction until the same has moved independently of the sliding bar to the extent of its slotted ear. This causes the locking-lever to be freed from its locking-pin, and then, by continuing the pull, the sliding bar G is drawn forward, consequently turning the curved lever on its fulcrum, and causing its free end to be outside of and removed from the face-plate. When the parts are in these positions the ordinary ring of the neck-yoke is slipped on the lock.

ing-lever, the pull-stem is then released for causing the sliding bar to be forced back by its spring, and the end of the locking-lever to be projected into the cavity B for engagement with the locking-pin.

The draft strain of the neck-yoke is borne by a stud or projection, P, on the plate D.

The locking-lever may be provided with a thumb-piece, g, for enabling the same to be operated by hand after the pull-pin has been released; but generally the latter will be sufficient and more convenient for the purpose, as it is located at the front of the pole, within easy reach.

By the arrangement of devices shown neck-yokes may be detached from poles without going between the draft-animals.

What I claim is—

1. The draft attachment for carriage-poles, consisting of the attaching-plates C D, cap E, curved locking-lever F, sliding spring-retracted bar G, and pull-stem K, all combined with a pole, substantially as and for the purpose specified.

2. In combination with the locking-lever F and sliding bar G, the independently-movable spring-retracted pull and locking stem or pin K, substantially as shown and described.

In testimony that I claim the foregoing I have hereunto set my hand.

MARIA DUNHAM.
